UNITED STATES PATENT OFFICE.

HEINRICH SCHULZ, OF WORMS, GERMANY, ASSIGNOR TO FIRM CORNELIUS HEYL, OF WORMS, GERMANY.

METHOD OF DRYING VARNISHED (PATENT) LEATHER.

1,353,937.

Specification of Letters Patent. Patented Sept. 28, 1920.

No Drawing.

Application filed December 12, 1916. Serial No. 136,410.

To all whom it may concern:

Be it known that I, HEINRICH SCHULZ, chemist, subject of the German Emperor, residing at No. 57, Alzeyerstrasse, Worms, Germany, have invented certain new and useful Improvements in Methods of Drying Varnished (Patent) Leather, of which the following is a specification.

In the specification of German Patent 10 284605 a method of drying varnished (patent) leather has been disclosed according to which the leather dried in an oven is exposed for further drying to the simultaneous action of preferably ultraviolet light 15 and ammonia vapors. In carrying out this method in practice it has been observed that, on the one hand, no ozone odor is produced, and, on the other hand, also the characteristic odor of the ammonia almost completely disappears. This led to further observations the result of which was the recognizing of the fact that, when quartz light 20 and ammonia are employed together, the latter undergoes certain chemical changes, 25 by which derivatives of ammonia (hydrazin) and finally nitrogen are produced, which substances yield, as has been found, extremely favorable drying results.

The present invention accordingly resides in employing, in place of ammonia, derivatives of ammonia or pure nitrogen (which is the final product of chemical decomposition of ammonia), whereby a much more rapid drying can be effected than is possible with ammonia. It has also been discovered, 35 moreover, that other inactive gases may be substituted for the pure nitrogen.

I claim:

1. The herein-described method of drying varnished leather, which consists in subjecting the leather to the simultaneous action of ultraviolet rays and hydrazin.
2. The herein-described method of drying varnished leather, which consists in subjecting the leather to the simultaneous action of light rays and hydrazin.
3. The herein-described method of drying varnished leather, which consists in subjecting the leather to the simultaneous action of ultraviolet rays and a gaseous derivative of ammonia.

In testimony whereof I affix my signature.

HEINRICH SCHULZ.
